Hitchcock & Bement,

Making Shoes,

Patented July 30, 1811.

Samuel B. Hitchcock & John Bennett
Letters Patent

The following is a full description of the sole and making part of the same, containing a description of the words of the said Samuel B. Hitchcock and John Bennett, the nature of their art and mystery of their sole making.

The upper part of the boot or shoe being sewed together as was formerly done, is put on a last, having the inner sole laced to it, and is pegged to the inner sole. The laces which lace the inner sole to the last are then drawn out, the out or sole laid on and laced to the last. It is then pegged quite round from side to side, with one or more rows of wooden pegs, made of hard seasoned timber equal in size from end to end and driven obliquely quite through to the last. The different pieces of leather to compose the heel are each pegged on separately with the same kind of pegs, made in the same manner, driven in the same direction, but not always through to the last. The inner ends of the pegs are smoothed with an iron instrument made for the purpose.

Witness,

Wm. F. Hastings, R. Brandon,
Francis Treat

Samuel B. Hitchcock, for
John Bennett, Mfg.
